UNITED STATES PATENT OFFICE.

WILLIAM W. ROBERTSON, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

LOOM TEMPLE.

Application filed March 6, 1922. Serial No. 541,329.

To all whom it may concern:

Be it known that I, WILLIAM W. ROBERTSON, a subject of the King of Great Britain, residing at Worcester, in the county of 5 Worcester and State of Massachusetts, have invented a new and useful Loom Temple, of which the following is a specification.

This invention relates to loom temples and to a novel arrangement and disposition 10 of such temples relative to the fabric in the loom.

Loom temples, as is well known, perform the function of holding the woven fabric at full width near the fell of the fabric, so that 15 the woven threads may pass freely through the reed openings. My invention relates particularly to wide looms for weaving Axminster carpets but is of general utility in looms weaving any wide heavy fabric.

20 One object of my invention is to provide temples disposed below the fabric and engaging the fabric on the under or back side thereof. Another object of my invention is to provide a plurality of temples mounted 25 in spaced relation across the width of the loom and engaging the fabric at each selvage and also at intermediate points in the width of the fabric.

30 My invention further relates to the provision of means by which the intermediate temples may be adjusted vertically toward and from the fabric.

A preferred form of my invention is 35 shown in the drawings in which—

35 Fig. 1 is a plan view of parts of a loom, illustrating my improved construction;

Fig. 2 is a sectional elevation taken along the line 2—2 in Fig. 1; and

40 Fig. 3 is an enlarged detail elevation taken along the line 3—3 in Fig. 1.

Referring to the drawings, I have shown a cloth-board 10 which may be suitably supported in any convenient manner and which extends across the loom directly beneath the 45 carpet or fabric F. The usual lay 11 with its reed 12 and the usual comb 13 are mounted in operative relation with the cloth-board 10 as indicated in Fig. 3.

The temples 14, 15, 16 and 17 are mounted 50 in the cloth-board so that the upper surfaces of the rolls project slightly above the upper edge of the cloth-board, as shown in Fig. 3.

55 The temples are preferably arranged in a single line extending transversely of the

fabric with the temple rolls rotatable in planes obliquely disposed with reference to the direction of travel of the fabric and with the rolls of the temples 14 and 15 oppositely disposed with reference to the 60 rolls of the temples 16 and 17.

The outer temples 14 and 17 engage the opposite selvages of the fabric on the under side thereof and act to prevent shrinkage of the fabric as it leaves the reed. The 65 intermediate temples 15 and 16 are of material assistance in relieving the strain on the temples 14 and 17 particularly when used with wide heavy fabric such as Axminster carpet. It will be understood that 70 any desired number of intermediate temples may be used to suit particular conditions.

The outer temples 14 and 17 commonly 75 rotate in fixed positions at the ends of the cloth-board 10 but the intermediate rolls 15 and 16 are mounted in slots 18 in the cloth-board and are engaged by adjusting screws 20 by which their vertical positions may be determined. By slightly raising the intermediate temples, the rolls thereof may 80 be caused to more firmly engage the fabric.

My invention is particularly designed for use with pile fabric which is woven face up, the temple rolls thus engaging only 85 the back or unfinished side of the fabric. As the fabric leaves the edge of the cloth-board, it is drawn firmly over the temple rolls and no casing or other provision is necessary for holding the fabric in engagement with the rolls.

Having thus described my invention, I 90 do not wish to be limited to the details herein disclosed otherwise than as set forth in the claims, but what I claim is:—

1. In a loom, a cloth board having a projecting upper edge over which the fabric is drawn and a plurality of temples mounted in said cloth board and projecting therethrough to engage the lower surface of the fabric as it is drawn over the edge 100 of said cloth board.

2. In a loom, a pair of temples engaging the fabric at the selvages thereof, and additional temples engaging the fabric at intermediate points in the width thereof.

3. In a loom, a pair of temples engaging the under side of the fabric at the selvages thereof and additional temples engaging the under side of the fabric at intermediate points in the width thereof.

4. In a loom, a pair of temples engaging the under side of the fabric at the selvages thereof, additional temples engaging the under side of the fabric at intermediate points in the width thereof, and means to adjust said intermediate temples toward and away from the fabric.
5. In a loom, a cloth board having a projecting upper edge over which the fabric is drawn, a plurality of temples mounted in said cloth board and projecting therefrom to engage the lower surface of the fabric as it is drawn over the edge of said cloth board and means to independently adjust each end of certain of said temples vertically in said cloth board toward and from the fabric.
6. In a loom, a plurality of temples axially aligned transversely of the fabric, said temples engaging the fabric at each selvage and at intermediate points in the width thereof.
7. In a loom, a plurality of temples axially aligned transversely of the fabric and engaging the fabric at each selvage and at intermediate points in the width thereof, the rolls of each temple being rotatable in planes oblique to the direction of movement of the fabric and said planes being oppositely disposed at each side of the center line of the fabric.

In testimony whereof I have hereunto affixed my signature.

WILLIAM W. ROBERTSON.
